UNITED STATES PATENT OFFICE.

JULES CHARLES LEVASSEUR, OF MILIANAH, ALGERIA.

WATCH-REGULATOR.

SPECIFICATION forming part of Letters Patent No. 355,093, dated December 28, 1886.

Application filed August 19, 1885. Serial No. 174,788. (No model.) Patented in France October 13, 1884, No. 164,879.

To all whom it may concern:

Be it known that I, JULES CHARLES LEVASSEUR, of Milianah, Algeria, have invented a new and Improved Watch-Regulator, (for 5 which I have received Letters Patent of France, No. 164,879, dated October 13, 1884,) of which the following is a full, clear, and exact description.

The object of my invention is to provide 10 means for adjusting the balance-regulator of a watch without opening the case.

The invention consists of a segmental gear-wheel attached to or formed upon the regulator, and mechanism in gear therewith, whereby 15 the regulator may be adjusted by means of the winding-stem when arranged for setting the hands, or by an independent stem fitted in the case; also, in the combination therewith of an index or tell-tale visible on the dial to indicate 20 the position of the regulator; and, finally, in the construction and combination of parts, as hereinafter fully described, and then pointed out in the claims.

Reference is to be had to the accompanying 25 drawings, forming a part of this specification, in which similar letters of reference indicate corresponding parts in all the figures.

Figure 1 is a face view of a stem-winding watch to which my improvement has been applied. Fig. 2 is a rear view of the same, parts 30 being broken away to reveal the construction. Fig. 3 is an edge view of the same, partly in section, on the broken line $\alpha\alpha$, Fig. 2. Fig. 4 is a front view, the case and dial being partly 35 broken away to disclose the arrangement of parts; and Fig. 5 is a rear view of a key-winder, the case being partly broken away to show the application of the improvement.

In the case A of the stem-winder is mounted 40 the usual winding-stem, B, connected with the mainspring mechanism, and adapted to be disconnected from the same and geared with the hand-setting mechanism by means of the usual push-button, C, all in the ordinary manner.

On the arbor D of the minute-hand is fixed 45 the pulley E, around which is passed an endless chain, F, which also passes loosely around a pulley, G, mounted on an arbor, H, on which is also mounted a spur-wheel, I. The spur-wheel I engages with a pinion, J, mounted on a spindle, J', on which is also mounted a second pinion, K, which engages with a segmental

gear-wheel, L, attached to or formed upon the regulator L'. The latter is of the ordinary description for adjusting the tension of the hair-spring acting on the balance-wheel. 55

The pinion J on the spindle J' is in gear with a segmental rack or gear wheel, M, fixed upon a spindle, M', mounted in suitable bearings in the casing of the works. The forward end of 60 the spindle M' projects through the dial and carries a pointer or index, M'', which registers with the divisions of a segmental scale, M², on the face of the dial. The index M'' thus turns with the regulator and serves to indicate the 65 position of the same, the scale M² being marked in the usual manner to indicate the direction and distance the regulator is to be turned to make the watch run slower or faster. With the pinion K, with which the rack L is in gear, 70 also engages a crown-wheel, N, mounted on the inner end of a stem, N', turning in suitable bearings in the works and having its outer end squared to receive a sliding head, N'', projecting 75 through the rim of the case A.

To the inner end of the sliding head N'' is attached the free end of a flat spring, O, fixed in the casing, which spring tends to hold the head in its outer position projecting from the casing, so as to be capable of easy adjustment by 80 the fingers. The spring O is pressed inward, to withdraw the head N'' within the casing, by a button or push-piece, P, mounted to slide on the rim of the case, and provided on its inner part with a cam-piece, P', which, when operated, acts upon the flat spring O to retract the head N'', the button P sliding over the end of and concealing the same. 85

Adjacent to the endless chain F is pivoted 90 an angle-lever, Q, the outer arm of which projects through the rim of the case and carries a sliding button or push-piece, Q'.

The inner arm of the lever Q is made springy, and carries a small rotary disk or pulley, Q², adapted to be pressed against and tighten the 95 endless chain F when operated by the button Q, thus causing the spur-wheel I, in gear with the regulator, to turn coincidently with the minute-hand arbor when the hands are being adjusted by means of the winding stem B. 100

In Fig. 5 I have illustrated a key-winding watch to which my device has been applied, the arrangement of the independent adjusting-stem N' and its crown-wheel N being the same

as in the stem-winder, except that the sliding head N^2 is omitted and the stem squared to receive the key-shank; or such head may be used, if desired. The stem, when not in use, is concealed by the sliding button P' .

If preferred, the regulator may also be connected with the hand-arbor, as in the stem-winder, and in the same manner.

The operation is as follows: To adjust the regulator without disturbing the hands, the sliding button P is pushed back to allow the head N^2 of the stem N' to be projected from the rim of the case by the spring O , and the stem N' is then rotated by its head to turn the segmental rack on the regulator-spindle to the proper position, as indicated by the index on the dial-face. To adjust the regulator when the hands are being set forward or backward, and thus make the watch run faster or slower, respectively, the push-button C is operated to disengage the winding mechanism and throw the hand-arbor in gear with the stem B , in the usual manner. The button Q is also moved to tighten the endless chain and connect the minute-hand arbor with the regulator, as before stated, so that when the minute-hand is turned the regulator is adjusted simultaneously therewith, and the error and rate of the watch are compensated for coincidently. The chain F , when free from its tension-disk, is slack, and the hands can then be set in the usual manner without disturbing the regulator.

Having thus fully described my invention, I claim as new and desire to secure by Letters Patent—

1. In a watch, the combination, with the hand-arbor mechanism and the balance-regulator, of gearing connecting the regulator with

the hand-arbor, endless chain or belt mechanism interposed in the said gearing, and means for tightening the belt or chain for adjusting the regulator coincidently with the hands, substantially as specified.

2. In a watch, the combination, with the regulator, of a segmental rack or gear wheel on the same, a pinion in gear with said rack or gear wheel, a shaft carrying the pinion, a second pinion on said shaft, a second rack in gear with the latter pinion, and an index or pointer turned by the latter rack and registering with a scale on the watch-dial, substantially as shown and described.

3. In a watch, the combination, with the case and the balance-regulator, of an externally-adjustable stem connected with the same, a sliding operating-head on the stem, a spring connected with the sliding head, and a sliding button acting on the spring and arranged to cover the head, substantially as shown and described.

4. In a watch, the combination, with the case, the balance-regulator, and the minute-hand arbor, of gearing connecting the same with the regulator, pulleys, and an endless chain or belt interposed in said gearing, and a pivoted lever carrying a friction-disk for tightening the belt and provided with a push-piece for operating it, substantially as shown and described.

The foregoing specification of my improved watch-balance regulator signed by me.

JULES CHARLES LEVASSEUR.
